CLAIM

The ornamental design for a hair iron, as shown and described.

DESCRIPTION

FIG. 1 is a perspective view taken from the top, front, and left side of the hair iron of the present invention, shown in its closed configuration.

FIG. 2 is a perspective view of the hair iron of FIG. 1, taken from the top, front, and left side, shown in its opened configuration in accordance with the present invention.

FIG. 3 is a left side elevational view of the hair iron of FIG. 1, shown in its closed configuration.

FIG. 4 is a left side elevation view of the hair iron of FIG. 3, shown in its opened configuration.

FIG. 5 is a right side elevation view of the hair iron of FIG. 1, shown in its closed configuration.

FIG. 6 is a bottom plan view of the hair iron of FIG. 1, shown in its closed configuration.

FIG. 7 is a top plan view of the hair iron of FIG. 1, shown in its closed configuration.

FIG. 8 is an enlarged front elevation view of the hair iron of FIG. 1, shown in its closed configuration.

FIG. 9 is an enlarged rear elevation view of the hair iron of FIG. 1, shown in its closed configuration.

FIG. 10 is a perspective view taken from the top, rear, and left side of the hair iron of FIG. 1, shown in its closed configuration; and,

FIG. 11 is a perspective view taken from the top, rear, and left side of the hair iron of FIG. 10, shown in its opened configuration.
